UNITED STATES PATENT OFFICE.

JAMES DUNCAN, OF COSHOCOTON, OHIO.

MOP-HOLDER.

SPECIFICATION forming part of Letters Patent No. 396,330, dated January 15, 1889.

Application filed March 20, 1888. Serial No. 267,895. (No model.)

To all whom it may concern:

Be it known that I, JAMES DUNCAN, a citizen of the United States, residing at Coshocton, in the county of Coshocton and State of Ohio, have invented certain new and useful Improvements in Mop-Holders, of which the following is a specification, reference being had therein to the accompanying drawings.

This invention relates to new and useful improvements in mop-holders; and the invention consists in the improved construction, all as more fully described, claimed, and shown in the drawings, in which—

Figure 1 is a perspective view of my improved device. Figs. 2 and 3 are modifications thereof in side elevation and vertical central longitudinal section.

A is the handle, and B is the cross-bar forming the fixed part of the mop-head and secured 20 to the handle by means of the socket C, integrally cast with the cross-bar B.

D is the sliding part of the mop-head, and consists of the serrated clamping-bar, with the arms E projecting at right angles therefrom, 25 which arms engage in slots formed in the ends of the cross-bar B of the mop-head and in the guide-bearings F, formed on the outer ends of the cross-head.

G are clamping-levers pivotally secured at 30 their inner ends to the mop-head and provided at their outer ends with the grooved abutments H, by means of which they may be engaged upon the inner edges of the arms E, as shown.

35 In practice, the parts being constructed and arranged as shown and described, they are intended to operate as follows: If the clamping-levers G are disengaged from the arms E by throwing them back against the handle, the 40 clamping-bar D can be freely moved from or toward the cross-bar to form a suitably large opening, into which the mop-cloth may be engaged. Then by clamping the clamping-bar against the cross-head and throwing the levers 45 G into engagement with the arms E the cloth is firmly locked in position to hold it from any displacement in use.

It is obvious that by arranging the clamping-levers G to operate at a nominal incline great force may be obtained to lock the arms 50 E in fixed position, which, by the locking action, are naturally slightly sprung. To prevent breakage under this action, I make the device preferably of malleable iron or other suitable material.

55 In Fig. 2 I show a modification of the clamping-lever G, which is there merely represented by the spring I operating in a similar manner, as the clamping-lever, but fixedly secured at the inner ends to the mop-head. With this 60 construction I preferably provide the mop-head with the cam J, which is actuated by the crank-handle K to throw the spring out of its locked position, and, if desired, the same device may be applied to the construction shown 65 in Fig. 1.

Another means of locking the sliding part of the mop-head is shown in Fig. 3, where it is accomplished by means of the spring-latch laterally slidingly secured in a recess in the 70 cross-bar of the mop-head and adapted to engage in serrations upon the inner edges of the arms E. If desired, similar serrations may be used in connection with the other constructions shown in Figs. 1 and 2.

75 What I claim as my invention is—
In a mop-holder, the combination, with the fixed part of the mop-head, consisting of the cross-bar B, slotted upon its outer ends and provided with the guide-bearings F, of the 80 sliding part of the mop-head, consisting of the cross-bar D, provided with the arms E, projecting at right angles therefrom and slidingly engaging with the fixed part of the mop-head, and a locking device, as the clamping-levers G, adapted to engage with the arms E, substantially as described.

In testimony whereof I affix my signature, in presence of two witnesses, this 18th day of February, 1888.

JAMES DUNCAN.
